UNITED STATES PATENT OFFICE.

ERNEST C. SPRINGER, OF MASON CITY, IOWA, ASSIGNOR OF ONE-HALF TO
JOSEPH J. CLARK, OF MASON CITY, IOWA.

MACHINE FOR TAMPING RAILROAD-TIES.

SPECIFICATION forming part of Letters Patent No. 727,013, dated May 5, 1903.

Application filed July 22, 1902. Serial No. 116,530. (No model.)

To all whom it may concern:

Be it known that I, ERNEST C. SPRINGER, a citizen of the United States, residing at Mason City, in the county of Cerro Gordo and State 5 of Iowa, have invented certain new and useful Improvements in Machines for Tamping Railroad-Ties; and I do hereby declare the following to be a full, clear, and exact description of the invention, such as will enable others skilled in the art to which it appertains to 10 make and use the same.

The present invention relates to improvements in mechanism for use in railway construction, and more particularly to such mechanism employed for tamping or spiking purposes.

The object in view is the provision of means for tamping a railway road-bed or for spiking the rails to the ties, means being provided for 20 adjusting the tamping means to various angles.

With this and other objects in view the invention consists, in combination with a suitable carriage, of tamping means arranged 25 thereon and guides for said tamping means for securing the same in various adjustments.

It further consists, in combination with a suitable carriage, of a tamping-plunger mounted thereon, means for reciprocating said plunger, a framework carrying said plunger, a guide supporting said framework, and means for adjusting said guide to various positions.

It also consists in certain other novel constructions, combinations, and arrangements of parts, as will be hereinafter fully described and claimed.

In the accompanying drawings, Figure 1 represents a top plan view of a tamping or 40 spiking mechanism embodying the features of the present invention, parts being broken away. Fig. 2 represents a view in side elevation of the same. Fig. 3 represents a detail view of the tamping-plungers. Fig. 4 represents a detail view of the tamper-supporting beam.

Referring to the drawings by numerals, 1 indicates any suitable carriage, preferably in the form of a car provided with the usual 50 flanged wheels and formed with a drop or depending portion 2 intermediate of its length.

Upon each side of the car or carriage 1 are arranged vertical standards 3, rising from the bottom of drop 2 and supporting horizontal transverse beams 4, suitably spaced apart 55 and carrying at each end a beam 5, arranged longitudinally of the car, but transversely of the beams 4. Carried by the ends of each of the beams 5 are guides 6, formed with pawls 7, controlled by suitable levers 8, adapted 60 to engage notches 9 in the beam 5.

Between the beams 4, near each end thereof, is arranged a vertical cylinder 10, provided with a suitable piston-head 11, carrying a vertically-moved piston 12, which in turn carries 65 the beam 13, parallel with and placed above the beam 5. The beam 13, as will be apparent from Fig. 4, is made up preferably of two parallel plates 13^a, spaced apart and secured together by a center web 13^b, which web is 70 apertured at 13^c for receiving the piston 12, said piston and web being rigidly secured together. The plates 13^a are formed with longitudinal slots 13^d and a series of apertures 13^e for purposes hereinafter mentioned. 75 Each end of the beam 13 carries an adjustably-mounted cylinder 14, pivotally attached to a transversely-arranged supporting-lever 15, which extends through its respective slots 13^d and forms supporting-bearings for said cylinder 80. Each lever 15 is provided with any suitable pawl 16 for engaging one of the apertures 13^e for locking the cylinder 14 in any adjusted position against lateral movement.

Extending downwardly from each cylinder 85 14 is a suitable framework 17, formed with guideways for a tamping-plunger 18, which plunger is connected to a suitable piston 19, carried by a piston-head 20 within the cylinder 14. The framework 17 fits within its respective guide 6 and is adapted to be adjusted to various planes by the adjustment of said guide longitudinally of its beam 5, the framework 17 swinging upon the pivot of the cylinder 14, the guide 6 being pivotally attached 95 to its adjusting-lever 8. Each cylinder 14 is provided with an intake-port 20^a, preferably connected by any suitable flexible connection with any suitable source of supply, a slide 21 controlling the admission of pressure to the 100 cylinder through said port. A bracket 22 is secured, preferably, to the end of the cylinder

14 and carries a pivotally-mounted operating-arm 23, attached to a bell-crank lever 24, which has its free end slotted and engaging the stem 25 of the valve 21 and inclosing any suitable 5 stud carried by said stem. A suitable bracket 26 guides the movement of the free end of the stem 25, and a suitable spring 27 is interposed between said bracket 26 and the slotted end of said bell-crank lever. A suitable 10 spring 29 is arranged, preferably longitudinally of the piston-rod 19, within the framework 17 and connected with said rod for moving the same longitudinally upward. A rod 28 extends upwardly from the piston 19 and engages the lower face of operating-arm 23, so that the upward pull of spring 29 normally causes said rod 28 to lift arm 23 and admit steam into the cylinder 14. Immediately 15 upon such admission of steam the piston 19 moves downwardly, permitting the spring 27 to act on lever 24 and close the intake 20^a, at the same time opening any suitable exhaust-port, which may be a common tube, as indicated in Fig. 2, the valve not being shown. By this arrangement it will be seen that when pressure is supplied to the intake-port 20^a the piston 19 will be automatically reciprocated with comparatively short strokes and in rapid succession.

30 Each beam 5 rests by weight upon beams 4 4 and may be moved laterally thereon. Suitable supply-pipes 30 30 lead to the respective ends of each of the cylinders 10, suitable three-way valves 31 31 being interposed 35 in the length of said supply-pipes and provided with operating-handles 32 32 for controlling the admission of pressure to said cylinder. It will thus be seen that pressure may be introduced into each cylinder 10 for lifting the beam 13 carried thereby and with it the plungers 18 and their operating mechanism, so as to raise the same to a horizontal plane above the rail upon which the wheels of the car or carriage rest. The beams 4 4 40 are provided with rack-bars 33 33, and each beam 5 is provided with a pinion 34, meshing with its respective rack-bar 33, any suitable means, as a crank 34^a, being provided for rotating said pinion, whereby the parts raised 45 by the movement of the piston-head 11, as above described, will be moved in a horizontal plane for the required distance. After such movement the valve 31, controlling the supply to the lower end of the cylinder 10, 50 may be reversed for permitting the exhaust of the steam from the cylinder, and pressure may then be admitted into the opposite end of the cylinder for bringing the parts down to their normal horizontal plane.

55 60 In practice I may provide any suitable pressure-supply tanks 35 35 or may employ any other source of supply for the operation of the parts described.

It is believed that the operation of the present improved tamping or spike device will be readily comprehended, the same being somewhat as follows: The car or carriage 1 is

70 moved by means of a motor carried thereby or any other suitable source of power to the point of operation, when the piston-head 11 70 is forced to the lower end of the piston 10, bringing the tamping-plungers 18 into position upon their respective sides of the tie. Fluid-pressure is supplied to the cylinders 14, a series of short rapid strokes of the plungers is produced, and the road-bed will be readily tamped, the movement of each pair of tamping-plungers being preferably approximately simultaneous, so as to crowd the ballast or other substance in opposite directions beneath the rail at the same time. When it is desired to employ the device as a spiking means, it is only necessary to raise the plungers 18 to a slightly higher plane and cause them to strike the heads of the spikes 80 to be driven. If it is desired to alter the angle or incline of the plunger 18, the guide 6 is moved longitudinally of the beam 5 and locked in position by the pawl 7 engaging the desired notch of the series of notches 9. 90 However, it may be found desirable to swing the lower end of the plunger 18 to an angle greater than will be permitted by the adjustment of the guide 6, and the same is accomplished by a movement of the cylinder 95 14, the lever 15 being slid along its respective slot 13^a. It will be seen that by this means the tamping-plunger may be moved from a diagonal plane in one direction to a plane of an equal angle in the opposite direction, a great deal of freedom thereby being permitted in the use of the tampers, whereby the tamping of the road-bed is greatly facilitated. It will be further observed that each plunger 18 may by the proper adjustment of its supporting parts be caused to assume a vertical plane and may be reciprocated while in such plane, so as to more effectually perform the spiking operation when desired. When the bed has been sufficiently 100 tamped on one side of a rail, the beam 13 may be lifted through the movement of the piston 12, whereby the plungers 18 may be raised above the horizontal plane of the rail, and the entire mechanism may be caused to 105 move laterally through the operation of the gear 34 meshing with the rack 33. When the parts have been moved laterally the desired distance, the beam 13 may be dropped and the tampers set into operation. 110

115 Although the details of one particular embodiment of a tamping mechanism have been specifically set forth, yet it will be understood that any suitable changes or minor variations therefrom may be made without departing from the spirit and scope of the invention. 120

125 Having thus fully described my invention, what I claim as new, and desire to secure by Letters Patent, is—

130 1. In a tamping or spiking mechanism, the combination with a suitable carriage or car, of a plunger arranged thereon, a framework pivoted to swing from an inclined plane in

one direction to a similar plane in another direction, and carrying said plunger, and means for reciprocating the plunger longitudinally within said framework, substantially as described.

2. In a tamping or spiking mechanism, the combination with a suitable carriage or car, of a plunger mounted thereon, a pivoted framework carrying the same, means for reciprocating said plunger longitudinally of said framework, and means for moving said framework upon its pivot from an inclined plane in one direction to an oppositely-inclined plane, substantially as described.

3. In a tamping or spiking mechanism, the combination with a suitable support, of a pair of reciprocating plungers, a pivoted framework carrying each of the same, and means for moving the plungers in their respective framework in downwardly-converging planes, each of said frameworks being capable of being swung upon its pivots sufficiently to cause the plungers to reciprocate in downwardly-diverging planes, substantially as described.

4. In a mechanism of the class described, the combination with a suitable support, of a framework arranged therein, a plunger finding guideways in said framework, a guide retaining said framework in position, and means for adjusting said guide for positioning said framework in various planes, substantially as described.

5. In a mechanism of the class described, the combination with a suitable support, of a beam arranged thereon, a guide carried thereby, means for adjusting said guide longitudinally of said beam, and a reciprocating plunger carried by said guide, substantially as described.

6. In a mechanism of the class described, the combination with a suitable support, of a reciprocating plunger carried thereby, means for lifting said plunger to various horizontal planes, and means for adjusting said plunger laterally, substantially as described.

7. In a mechanism of the class described, the combination with a suitable support, of a beam carried thereby, a reciprocating plunger carried by said beam, and means for adjusting said plunger and beam laterally, substantially as described.

8. In a mechanism of the class described, the combination with a suitable support, of a beam mounted thereon, a reciprocating plun-

ger pivotally carried by said beam, means for adjusting said plunger to various planes upon said pivot, and means for adjusting said beam and plunger laterally, substantially as described.

9. In a mechanism of the class described, the combination with a suitable support, of a reciprocating plunger arranged thereon, a framework carried by said plunger, means pivotally and slidably supporting said framework intermediate of its length, a slotted beam, means pivotally connecting the free end of said framework with said slotted beam, and means for reciprocating said plunger, substantially as described.

10. In a mechanism of the class described, the combination with a suitable support, of a slotted beam carried thereby, a cylinder, means carried by said cylinder engaging the slot of said beam for supporting the cylinder pivotally whereby the cylinder may be moved longitudinally of the beam, a piston carrying said cylinder, a plunger connected with the said piston, and means for guiding said plunger in its movement, substantially as described.

11. In a mechanism of the class described, the combination with a suitable support, of a beam arranged thereon, a beam arranged transversely of said beam and carrying a reciprocating plunger, a rack-bar secured to said first-mentioned beam, and a gear-wheel secured to said second-mentioned beam meshing with said rack-bar, and means for rotating said gear for causing said second-mentioned beam with its plunger to move laterally, substantially as described.

12. In a mechanism of the class described, the combination with a suitable support of a cylinder arranged thereon, a piston carried thereby, tamping means controlled by said piston, a valve controlling the intake pressure to said cylinder, an arm for actuating said valve in one direction, a spring normally pressing the said valve in an opposite direction, and means controlled by said piston for actuating said arm for automatically effecting reciprocation of said piston, substantially as described.

In testimony whereof I hereunto affix my signature in presence of two witnesses.

ERNEST C. SPRINGER.
